BARREL TILTING AND SUPPORTING DEVICE

Filed June 9, 1927

UNITED STATES PATENT OFFICE

ALBERT J. LAUGHLIN, OF HARROLD, SOUTH DAKOTA

BARREL TILTING AND SUPPORTING DEVICE

Application filed June 9, 1927. Serial No. 197,594.

This invention relates to new and useful improvements in devices constructed for disposition beneath a barrel at its edge when the same is disposed vertically upon a floor or support to facilitate the tilting of the barrel to a substantially horizontal position and for maintaining the barrel in such a position so that the contents thereof may be readily dispensed.

In carrying out my invention I have provided a highly novel, simple, and inexpensive device of this character that is believed by me to be a substantial improvement over generally similar barrel handling devices heretofore used and in some instances patented.

In the drawing wherein like reference characters indicate corresponding parts throughout the several views:

Figure 1 is a side elevation of my improved device in position for supporting a barrel relatively horizontally thereon, the barrel being fragmentarily disclosed in dotted lines.

Figure 2 is a top plan view of the device, and

Figure 3 is a front end elevation thereof.

Now having particular reference to the drawing, the invention consists of a substantially rectangular shaped barrel supporting cradle indicated in its entirety by the reference character A. This cradle consists of a pair of spaced parallel side bars 5—5 interconnected at their forward ends by a cross bar 6, the upper edge of which is flush with the upper edges of the side bars as clearly indicated in Figures 1 and 2. The rear ends of these side bars 5—5 are interconnected by a cross bar 7, its upper edge being directly beneath the lower edges of said side bars 5—5, also see Figures 1 and 2.

Depending from the outer faces of the side bars 5—5 of said cradle directly forwardly of the cross connecting bars 7 is a pair of supporting legs 8—8. Depending from the outer faces of said side bars 5—5 in inwardly spaced relation with respect to the forward ends thereof are other legs 9—9. The legs 9—9 are slightly shorter than the legs 8—8, while the lower edges of all the legs are bevelled to have flush engagement upon the floor when the device is in horizontal position supported by said legs. By reason of the legs 9—9 being slightly shorter than the legs 8—8 the cradle A will be in an inclined position for supporting the barrel in such a position as indicated in Figure 1, and in which position the barrel rests upon the rear connecting bar 7 of the cradle A and upon a cross bar 10 arranged beneath the side bars 5—5 directly forwardly of the legs 9—9. In this position the forward end of the barrel will engage directly in back of the forward bar 6 of said cradle to prevent sliding of the barrel in a forward direction, the side bars 5—5 of the cradle preventing any rolling of the barrel therein.

Interconnecting each leg 8 and 9 at the opposite sides of the cradle is an inclined brace bar 11, each of which is anchored at its forward end to the lower end of the respective forward leg 9 and at its opposite end to the respective rear leg 8 directly beneath the rear cross bar 7 of the cradle A. Furthermore, the lower ends of the forward legs 9 are connected to the forward ends of the side bars 5—5 of the cradle by brace bars 13—13 which bars also function as rockers when the device is tilted upwardly so that the forward bar 6 of the cradle may be engaged beneath the edge of the barrel B when the same is disposed upon the floor in vertical position. After said bar 6 has been engaged beneath the edge of the barrel, the barrel and support may be rocked rearwardly assuming the position more clearly indicated in Figure 1, in which position the barrel is supported in slightly inclined horizontal position so that the contents thereof may be readily drained through the usual cock C.

It will thus be seen that I have provided a highly novel, simple, and inexpensive barrel tilting and supporting device that is well adapted for all the purposes heretofore designated, even though I have shown and described the invention as consisting of certain detail structural elements, it is nevertheless to be understood that minor changes may be made therein without affecting the spirit and scope of the appended claim.

Having thus described the invention, what I claim as new is:—

In a barrel tilting and supporting device of the class described, a cradle including a pair of parallel spaced side bars, forward and rear supporting legs secured at their upper ends to the outer faces of the respective side bars, the rear legs being attached to the side bars directly adjacent the rear extremities thereof, the forward supporting legs being secured to the side bars a suitable distance inwardly from the forward ends thereof, said supporting legs being disposed at right angles with respect to the side bars, the forward legs being shorter than the rear legs, the lower ends of the legs being beveled for flush engagement with the floor whereby the cradle is disposed in a slightly inclined position, cross bars extending beneath the side bars and secured to the respective pairs of supporting legs, an additional cross bar extending across the forward ends of the side bars and secured thereto, the upper edge of the last mentioned cross bar lying flush with the upper edges of the side bars and providing a stop for the barrel that rests on the aforementioned cross bars and between the side bars, braces extending between the lower ends of the forward legs and the intermediate portions of the rear legs, and additional braces extending between the lower ends of the forward legs and the forward extremities of the respective side bars.

In testimony whereof I affix my signature.

ALBERT J. LAUGHLIN.
